Patented Feb. 15, 1910.

UNITED STATES PATENT OFFICE.

LUDWIG STEPHANY, OF PHILADELPHIA, PENNSYLVANIA, ASSIGNOR OF ONE-HALF
TO DANIEL STAHL.

PNEUMATIC SCISSORS.

949,095.

Specification of Letters Patent. Patented Feb. 15, 1910.

Application filed December 26, 1908. Serial No. 469,260.

To all whom it may concern:

Be it known that I, LUDWIG STEPHANY, a citizen of the United States, residing in the city and county of Philadelphia, State of Pennsylvania, have invented a new and useful Pneumatic Scissors, of which the following is a specification.

My present invention consists of a novel construction of a pneumatic scissors by the 10 employment of which the cutting or severing of any desired fabric can be readily and quickly accomplished.

It further consists of a novel construction of pneumatic scissors wherein I employ a 15 turbine wheel with buckets, said turbine wheels being operatively connected with the movable blade of the scissors.

It further consists of a novel manner of 20 assembling the movable blade with the connecting rod whereby the movable blade may be quickly disconnected when it is desired to remove the same for grinding or inspection.

It further consists of a novel construction 25 of a stationary blade and novel means for securing the same to the casing of the tool.

It further consists of novel means for 30 assembling the parts of the casing.

It further consists of other novel features 35 of construction all as will be hereinafter more fully described.

For the purpose of illustrating my invention I have shown in the accompanying 40 drawings preferred embodiments thereof which have given in practice satisfactory and reliable results, although it is to be understood that the instrumentalities of which my invention consists can be variously arranged and organized and that my invention is not limited to the exact arrangement and organization of such instrumentalities as herein shown and described.

Figure 1 represents a side elevation of a 45 pneumatic scissors embodying my invention, one portion of the casing having been removed and a portion of the device being shown in section. Fig. 2 represents a sectional view of Fig. 1. Fig. 3 represents a 50 section on line $x-x$ Fig. 2. Fig. 4 represents a perspective view of the stationary blade in detached position. Fig. 5 represents a perspective view showing more 55 clearly the manner in which the movable blade is removably secured to the means for

operating the same. Fig. 6 represents a section on $y-y$ of Fig. 1. Fig. 7 represents a side elevation partly in section of another embodiment of my invention. Fig. 8 represents a side elevation of a portion of a 60 pneumatic scissors showing another embodiment of my invention.

Similar numerals of reference indicate corresponding parts in the figures.

Referring to the drawings. Referring 65 first to Figs. 1 to 6 inclusive, 1 designates a pneumatic scissors embodying my invention, the same consisting of a casing member 2 to which a cover 3 is removably secured and in order to reduce the number 70 of fastening devices to a minimum the casing 2 is apertured as indicated at 4 and the cover 3 is provided with a hook 5 which is adapted to engage the aperture 4 to lock the parts in assembled position, it being seen 75 that by such a construction it is simply necessary to employ a single fastening device which engages the aperture 4 and fastening devices engaging the apertures 7 to 80 secure the parts of the casing in assembled position.

8 designates a conduit which is threaded or otherwise adapted to be connected with the motive liquid supply, said conduit being 85 secured to the casing member 2 in any suitable manner.

9 designates a stator which extends through the conduit 8 and at its inner end is provided with a flaring outlet the purpose 90 of which will hereinafter appear.

10 designates a wall in the stator 9.

11 and 12 designate ports which extend through the conduit 8 and the stator 9, said 95 ports being adapted to communicate at certain times with a groove 13 in the valve sleeve 14 which latter is provided with a stop member 15 which limits the rotation of the valve sleeve 14 by its abutting against the cover 31.

16 designates a turbine shaft which is 100 mounted in the casing member 2 in any suitable manner and to which is secured a turbine wheel 17 provided with buckets 18 which travel in proximity to the flaring outlet of the stator 9, whereby the motive fluid 105 passing from the stator 9, impinges against the buckets 18 and causes the rotation of the turbine wheel 17 as will be apparent to those skilled in this art.

19 designates an eccentric which is secured 110

in any suitable manner to the turbine wheel 17, said eccentric having mounted thereon a connecting rod 20 which is provided with an adjusting device 21 such as a turn buckle 5 or its equivalent, whereby the length of the connecting arm may be varied as desired. The connecting arm 20 has pivoted at its outer end a block 22 which is provided with a lug 23 preferably rounded, said lug 23 10 having at its outer end a transverse bar or strip 24.

25 designates the movable blade which is provided with a slot 26 and an aperture 27 having substantially the same contour as the lug 23 it being noted that a slot 28 is provided contiguous the aperture 27 whereby when the blade 25 is turned so that the aperture 28 coincides with the bar 24, the movable blade 25 may be quickly removed without the use of any tools. The blade 25 is provided preferably with an inclined cutting face 29.

In practice I preferably construct the casing of aluminum or other light metal and 25 in order that the fastening devices for securing the stationary blade 30 to the casing member 2 will not be liable to become disengaged therefrom, I provide plates 31 of metal which are secured to the casing member 2 in any desired manner, preferably by dovetailing the same to the casing member 30 as seen in Fig. 6.

The stationary blade 30 is provided with a cutting face 32 the lower portion of which 35 is rounded as indicated at 33. The blade 30 is also provided with a slot 34 which at its inner end has an enlarged diameter as indicated at 35.

37 designates apertures through the blade 40 30, it being noted that a portion of the lower wall of such apertures are retained as indicated at 38.

38 designates fastening devices such as screws, it being noted, as most clearly seen 45 in Figs. 1 and 6, that one face of the head of the screw has been cut away so that when the blade 30 has been placed in position on the nose of the casing member 2 that the fastening device 39 on being assembled in 50 position and given a half turn will cause the head thereof to engage against the wall 38 and maintain the stationary blade 30 in assembled position with respect to the casing member 2.

55 40 designates a guide block which is fastened to the casing member 2 by means of suitable fastening devices as the screws 41, it being understood that since the stationary blade 30 is provided with a slot 34 60 through which the guide member 40 passes, the stationary blade 30 may be removed from the casing member 2 without disturbing the guide member 40.

42 designates a plate to which a fastening device 43 is secured which latter engages

the guide block 40 and also if desired, the casing member 2, whereby when the parts are assembled the movable blade 25 is maintained in proper position with respect to the stationary blade 30.

44 designates a spring which is secured to the casing member 2 in any suitable manner, the free end of said spring engaging the movable blade 25 as seen in Fig. 2, thereby maintaining the two blades in operative relation at all times and preventing any excessive friction of the blade 25 against the plate 42.

The operation of this embodiment of my invention will now be readily understood 30 and is as follows: Having the parts in the position indicated in Fig. 1 it will be apparent that when the valve sleeve 14 is rotated to the position seen in Fig. 2, the motive fluid may pass through the conduit 8 85 to port 11, groove 14 in the valve sleeve 14, and port 12, through the flaring mouth of the stator 9 and impinging against the buckets 18 of the turbine wheel 17, will cause said turbine wheel to be rotated together with 90 its eccentric 19 thereby causing the reciprocation of the connecting rod 20 which as has before been explained is operatively connected with the movable blade 25 whereby the cutting face 29 will coact with the cutting face 32 of the blade 30 and the severing or cutting of the fabric or other article will be effected in a very efficient manner and with great rapidity, it being apparent that the speed with which the turbine wheel 17 100 is rotated will vary in accordance with the pressure of the motive fluid employed to actuate the tool. The exhaust fluid escapes to the atmosphere through ports 45 in the casing, the number of such ports as will be 105 apparent, varying in accordance with the size of such ports and their location.

In the embodiment seen in Fig. 7, I have shown a modified form of my invention 110 wherein the movable blade has an oscillating instead of a reciprocating motion. In this embodiment the motive fluid passes through the inlet 46, and when the valve 47 is actuated, which latter may be of any usual or conventional type, the motive fluid may 115 pass from the stator 48 to the buckets of the turbine wheel 49 thereby causing the rotation of such turbine wheel, it being seen that this wheel is mounted on a shaft 50 journaled in brackets 51 carried by the casing of the device. The wheel 49 is provided with an eccentric 52 on which is mounted the connecting rod 53 so that on the rotation of the turbine wheel the arm 53 will be reciprocated. The arm 53 is slotted as indicated at 54 and through this slot passes a set screw 55 thereby guiding the rod 53 during its reciprocation and since the slotted end 56 of the movable blade 57 is pivoted 120 at 58 to the stationary blade 59 and is piv- 130

oted at 69 to the arm 53 the blade 57 will be oscillated as desired.

In the embodiment seen in Fig. 8 the motive fluid passes from the stator 60 and impinges against the buckets of the turbine wheel 61, thereby causing said turbine wheel to be rotated on its shaft 62, thereby causing rotation of the eccentric 63 secured to said turbine wheel and the reciprocation of the connecting arm 64 mounted on said eccentric, it being seen that the connecting arm 64 is provided with a turn buckle 65 whereby the length of such arm may be adjusted.

The connecting rod 64 has its free end pivotally connected with the movable blade 66 which latter is pivoted at 67 to the stationary blade 68.

It will be noted that in the embodiment seen in Figs. 7 and 8 the movable blade has an oscillating motion instead of a reciprocating motion and while in Fig. 7 I have shown the movable blade as being provided with a slot 56 through which the screw 69 passes which engages the connecting rod 53 and have shown the connecting rod 53 as guided in its movement by the screw 55 which passes through the slot 54, it will be apparent that in Fig. 8 I have shown the connecting rod 64 as being directly connected with the movable blade 66.

I wish to call particular attention to certain novel features in the construction of my device whereby I am enabled to quickly take apart or assemble the cutting blades for the purpose of cleaning or grinding.

It will be seen that when the blade 42 secured to the fastening device 43 is turned the movable blade 25 may be turned on its pivot as indicated in Fig. 5 and when such blade 25 is partially rotated the slot 28 will register with the bar 24 so that such blade may be readily removed from the block 22 without necessitating the employment of any tools.

When it is desired to remove the stationary blade the fastening devices 39 are rotated a half turn so that the head thereof becomes disengaged from the wall 38, whereupon the stationary blade 30 may be readily lifted from its assembled position with respect to the casing member 2.

In the embodiment seen in Figs. 1 to 6 inclusive, I have shown all of the working parts as being carried by the casing member 2 so that when the cover 3 is removed all of the parts are readily accessible for the purpose of oiling, inspection or repairs.

When the cutting faces of the blade become worn the blades may be readily adjusted with respect to each other by actuating the turn buckle 21 as is hereinbefore described.

It will now be apparent to those skilled in the art that I have designed a novel and useful construction of a pneumatic scissors

which embodies the features of advantage enumerated as desirable in the foregoing description, and while I have, in the present instance, shown and described preferred embodiments thereof which have been found in practice to give satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent is:—

1. In a pneumatic scissors, a casing, a stationary blade having a slot and apertures therethrough, a fastening device adapted to interlock with said apertures and engaging said casing, a guide member seated in said slot and secured to said casing, a movable blade mounted on said guide and coacting with said stationary blade, a transverse bar secured to said guide block for maintaining said blade in operative relation, a block with which said movable blade is adapted to interlock, an adjustable connecting rod secured to said block, a turbine wheel mounted in said casing and to which said connecting rod is eccentrically connected, and means for conducting motive fluid to said wheel. 95

2. In a pneumatic scissors, a sectional casing in one section of which all of the moving parts are mounted, a turbine wheel rotatably mounted on said casing, an eccentric connected with said wheel, a connecting arm 100 mounted on said eccentric, means for adjusting the length of said arm, a movable blade with which said connecting arm is adapted to be interlocked, a stationary blade coacting with said movable blade and removably carried by said casing, and means for controlling the admission of motive fluid to said turbine wheel. 105

3. In a pneumatic scissors, a casing having a stationary blade removably secured thereto, the lower portion of the cutting face of said blade being rounded, a movable blade having an inclined cutting face adapted to coact with said stationary blade, a turbine wheel with buckets rotatably 115 mounted in said casing, an eccentric operatively connected with said wheel, an adjustable connecting rod mounted on said eccentric and operatively connected with said movable blade, and means for controlling the admission of motive fluid to said buckets. 120

4. In a pneumatic scissors, a sectional casing having an aperture in one section thereof, the other of said sections having a hook adapted to interlock with said aperture, a turbine wheel with buckets rotatably mounted in said apertured section, an eccentric operatively connected with said wheel, a connecting arm operatively connected 130

- with said eccentric, a movable blade to which said connecting arm is removably secured, means for adjusting the length of said connecting arm, a stationary blade removably carried by said casing, means for maintaining said blades in operative relation during their movement, and means for controlling the admission of motive fluid to said buckets.
- 10 5. In a pneumatic scissors, a casing, metal plates secured thereto, fastening devices engaging said metal pieces, a stationary blade having a slot and provided with apertures with which said fastening devices are adapted to interlock, a guide block seated in said slot, a movable blade mounted on said guide block, a connecting rod with which said blade is adapted to be interlocked, means for maintaining said blades in operative relation, a turbine wheel to which said connecting rod is eccentrically secured, and means for controlling the admission of motive fluid to said turbine wheel.
6. In a portable scissors, a casing, a stationary blade having a slot therein and provided with apertures, fastening devices adapted to interlock with said apertures and engaging said casing, a guide block seated in said slot, a movable blade having a slot and mounted on said guide block, a block having a lug adapted to interlock with said blade and to be removed therefrom on the partial rotation of said blade, and a fluid actuated motor operatively connected with said last named block for controlling the movement of said movable blade.
7. In a portable scissors, a casing, a stationary blade removably secured thereto, a guide block carried by said casing and passing through said blade, a movable blade having a slot and a communicating aper-
- ture and mounted on said guide block, a block having a lug adapted to be seated in said aperture and having a bar extending beyond the sides of said aperture to lock said block and blade in assembled position, and a fluid actuated motor connected with said block for actuating said blade.
8. In a pneumatic scissors, a casing, a movable member mounted therein, fluid actuated means for controlling the movement of said member, a connecting rod actuated by said member, means for varying the length of said connecting rod, a block to which said rod is pivoted, a movable blade removably carried by said block and having an inclined cutting face, a stationary blade removably carried by said casing and having a cutting face coacting with the cutting face of said movable blade, and means for preventing improper relative movement of said blades.
9. In a pneumatic scissors, a casing, a stator carried thereby, a rotor mounted within said casing in proximity to the stator, means for conducting motive fluid to the stator, a guide block carried by the casing, a fixed blade adapted to interlock therewith, a movable blade mounted on said guide block, means for maintaining said blades in operative relation to each other, an adjustable crank connection connected with the rotor, a block pivotally connected with the crank connection, and a transverse bar adapted to interlock with said movable blade whereby the latter may be moved therefrom without the use of tools.

LUDWIG STEPHANY.
